US00D951697S

(12) **United States Design Patent** (10) **Patent No.:** **US D951,697 S**
(45) **Date of Patent:** **** May 17, 2022**

(54) **NOODLE MAKING MACHINE**

(71) Applicant: **DONGGUAN ZHEN ZHONG KANG PRECISION TRANSMISSION TECHNOLOGY CO., LTD**, Dongguan (CN)

(72) Inventors: **Tangrong Ni**, Dongguan (CN); **Zhenhai Xie**, Dongguan (CN)

(73) Assignee: **DONGGUAN ZHEN ZHONG KANG PRECISION TRANSMISSION TECHNOLOGY CO., LTD**, Dongguan (CN)

(**) Term: **15 Years**

(21) Appl. No.: **29/749,117**

(22) Filed: **Sep. 3, 2020**

(51) LOC (13) Cl. **31-00**

(52) U.S. Cl. **USPC .....** **D7/381; D7/376**

CLAIM

The ornamental design for a noodle making machine, as shown and described.

DESCRIPTION

FIG. 1 is a front perspective view of a noodle making machine showing our new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in the drawings illustrate the portions of the noodle making machine which form no part of the claimed design.

1 Claim, 8 Drawing Sheets
